US00D753672S

(12) United States Design Patent
Kim

(10) Patent No.: US D753,672 S
(45) Date of Patent:  Apr. 12, 2016

(54) DISPLAY SCREEN OR PORTION THEREOF
WITH GRAPHICAL USER INTERFACE

(71) Applicant: Samsung Electronics Co., Ltd.,
Suwon-si, Gyeonggi-do (KR)

(72) Inventor: Regina Yoon-Joo Kim, Seoul (KR)

(73) Assignee: Samsung Electronics Co., Ltd. (KR)

() Term: 14 Years

(21) Appl. No.: 29/488,471

(22) Filed: Apr. 18, 2014

(30) Foreign Application Priority Data

Nov. 8, 2013 (KR) 30-2013-0056234

(51) LOC (10) Cl. 14-04

(52) U.S. Cl.

USPC D14/485

(58) Field of Classification Search

USPC D14/485-488

CPC G06F 17/24; G06F 17/30056; H04N
1/00198; H04N 21/234336

(57) CLAIM

I claim, the ornamental design for a display screen or portion thereof with graphical user interface, as shown and described.

DESCRIPTION

FIG. 1 is a front view of a display screen or portion thereof with graphical user interface, showing my new design; and, FIG. 2 is a front view of a display screen or portion thereof with graphical user interface, showing an alternative embodiment of my new design.

In the drawings, the broken lines depict environmental subject matter only and form no part of the claimed design. The dot-dash broken lines define boundaries of the claimed design and form no part thereof.

1 Claim, 2 Drawing Sheets
